UNITED STATES PATENT OFFICE.

MARSHALL B. LLOYD, OF MENOMINEE, MICHIGAN, ASSIGNOR, BY MESNE ASSIGNMENTS, TO HEYWOOD-WAKEFIELD COMPANY, OF BOSTON, MASSACHUSETTS, A CORPORATION OF MASSACHUSETTS.

MEANS FOR PRODUCING WOVEN REED ARTICLES.

Application filed August 20, 1920. Serial No. 404,800.

To all whom it may concern:

Be it known that I, MARSHALL B. LLOYD, a citizen of the United States, and a resident of Menominee, county of Menominee, and State of Michigan, have invented certain new and useful Improvements in Means for Producing Woven Reed Articles, of which the following is a specification.

My invention relates generally to the production of articles embodying therein a reed-like fabric, at least in part, and my invention relates particularly to the production of reed articles having a frame.

Cross reference is hereby made to applicant's pending application Serial No. 687,188, filed January 19, 1924, which claims certain of the subject matter herein disclosed but not claimed.

Heretofore in the production of reed articles, it has been customary to secure the stakes, forming one part of the fabric, in the frame at one end, leaving the other ends free, and then manually to weave the filler strands over and under the respective stakes by alternately passing the filler strand over one stake and under the next adjacent stake. This practice is relatively slow and laborious, and requires a considerable degree of skill on the part of the reed worker before rapid, satisfactory work can be accomplished.

It is an object of my invention to provide a method and means whereby reed fabric can be woven on the frame of the article in a rapid, durable and economic manner, and wherewith it shall be possible for unskilled workers to produce reed articles of durable character, of pleasing appearance, and with a rapidity heretofore attainable only after a long apprenticeship.

My invention consists generally in the steps, acts, and stated sequence thereof, and in the means for practicing the method, whereby the above named objects, together with others that will appear hereinafter, are attainable; and my invention will be more readily understood by reference to the accompanying drawings which illustrate what I consider, at the present time, to be the preferred embodiment thereof.

In said drawings:

Fig. 1, is a perspective view of a device embodying my invention,

Fig. 2, is a view similar to Fig. 1, but illustrating an article in the first steps of being woven thereon.

Fig. 3 is a somewhat diagrammatic view illustrating part of the article completed.

Fig. 4 is a sectional view substantially on the line 4—4 of Fig. 3.

Fig. 5 is a sectional view substantially on the line 5—5 of Fig. 3.

Fig. 6, is a view of the fabric completed and removed from the weaving apparatus.

Fig. 7 illustrates the completed fabric associated with frame members binding all sides.

Fig. 8 is a view substantially on the line 8—8 of Fig. 6; and

Fig. 9 is a perspective view of an arm chair produced by a method and means embodying my invention.

As a means of expediting the weaving operation, I prefer to provide a device in which the frame parts, on which the fabric is to be woven, can be properly held, and which shall be capable of coacting in the weaving operation. To this end I provide a base frame 1 having spaced uprights or standards 2 and 3 at the rear thereof. The base 1 is preferably provided with a groove 4 for co-action with one of the frame parts of the article. Reed articles are generally provided with a dowel-like frame, i. e., a frame composed of wooden members circular in cross-section, and I have illustrated such a construction in the drawings, but this it should be understood is by way of illustration and not by way of limitation. For this reason the groove 4 is a curved groove 90 and is adapted to receive one of the frame members such as 5.

I have chosen to illustrate the formation of one of the side panels of the arm chair shown in Fig. 9, and hence have applied the reference character 5 to the dowel frame part which corresponds to the frame part 5 shown in conjunction with the weaving operation. Secured to and upstanding from the frame member 5 will be found two frame members 6 and 7, respectively, the corresponding members in Fig. 9 being given similar reference characters. The member 5 is preferably held in place in the weaving apparatus as by means of the detachable clamps 8. In the frame member 5 a plural-

5
ity of spaced stake members 9 and 9' are secured, preferably by drilling holes in the member 5 and glueing the stake ends therein. These stakes may be composed of natural reed, of so-called fibre reed, or they may be composite stakes, as desired. Alternate stakes 9', as here shown, extend beyond the intermediate stakes 9 and they are secured temporarily to or in a bar-like member 10.
10 Any suitable temporary securing means may be provided and the means here shown are spring like clamp or clip members 11' which embrace both the bar 10 and the stakes. The bar 10, as is probably best shown in Fig. 8, is also drilled to permit placement of the stakes therethrough. The bar 10 may, if desired, be one of the frame members of the article, but, as here shown, is a temporary bar which is simply used for the weaving 20 operation. I shall now describe the weaving of the fabric.

Assuming the parts to be as shown in Fig. 2 the bar 10 is swung to one side of its normal vertical position. This forms 25 a shed in which the filler strand can be placed very quickly as it may be placed along a straight line. So soon as a filler strand is placed therein the bar 10 is moved to the opposite side of its normal vertical 30 position thus forming another shed in which the filler strand is likewise placed. The filler strand 11 may, if desired, be withdrawn from a spool or drum 12, as shown in Fig. 3, and is preferably passed around the outer sides of the standards 6 and 7 each 35 time there is a reverse movement imparted to the bar 10 and the stakes secured thereto.

I have also provided means for packing the filler strands after they are laid in place 40 which means here takes the form of a frame 12 which has end trunnion members 13 and 14 for co-action with bearings or holes provided in the standards 2 and 3. A plurality of bearings or holes 15 are provided 45 at different heights, in the members 2 and 3, so that the member 12 can be raised, if desired, as the weaving of the fabric progresses. The frame member 12 is provided along one edge with a plurality of serrations or teeth 16 which are spaced in accordance with the spacing of the stakes 9 and 9'. Thus as shown in Fig. 3 when the frame 12 is swung downwardly the serrations or teeth portions 16 extend in the 50 spaces between the stakes and hence engage the filler strands when the frame is pushed downwardly thereby quickly and properly packing the filler strands.

In this manner even an unskilled worker 60 can very rapidly produce the finest character of woven fabric as a part of the article frame. When the fabric has been woven to the desired height for example, as shown

in Fig. 6, if the bar 10 is the temporary one spoken of, it and the temporary fastening devices 11' are removed from the stakes and thereafter, as shown in Fig. 7, a frame member 17 is attached to the uprights 6 and 7 and the various stakes 9 and 9' secured thereto in any suitable manner. 65 70

The frame member 17 is here shown as of greater length than the frame member 5 because it is the upper frame member of the chair side and is necessarily of greater length in order that it may extend between the front chair frame member 18 and the rearwardly inclined back frame member 19. Frame members 5 and 17 may be secured to the other chair members 18 and 19 in any suitable manner. It will be understood 75 from the foregoing that other parts of the chair shown in Fig. 9 may be produced in the same manner and when the parts are secured together there is obtained a reed article in which the reed fabric is woven 80 around the frame members and hence is inseparably secured thereto. 85

The many advantages of the method and means herein shown and described will be apparent to those skilled in this art without 90 further comment.

I claim:

1. An apparatus for use in producing reed articles embodying therein, means for detachably securing an article frame member 95 thereto, and a member swingably attached to the apparatus and having filler strand packing portions thereon.

2. An apparatus for use in producing reed articles embodying therein, means for detachably securing an article frame member thereto, a member swingably attached to the apparatus and having filler strand packing portions thereon, and means for 100 adjusting the operative position of said 105 swingable member.

3. An apparatus for use in producing reed articles embodying therein a base, means for detachably securing an article frame member to said base, standards 110 upstanding from said base, and a member swingably mounted in said standards and having filler strand packing portions thereon.

4. An apparatus for use in producing 115 reed articles embodying therein a base, means for detachably securing an article frame member to said base, standards upstanding from said base, a member swingably mounted in said standards and having 120 filler strand packing portions thereon, and means for adjusting the operative position of said swingable member.

In testimony whereof, I have hereunto set my hand, this 26th day of July, 1920.

MARSHALL B. LLOYD.
